US00D591052S

(12) **United States Design Patent**
Lin

(10) **Patent No.:** US D591,052 S
(45) **Date of Patent:** ** Apr. 28, 2009

(54) **SHEET GOOD WITH SURFACE PATTERN**

(76) Inventor: **Chieh-Jen "Bruce" Lin**, 3F., No. 649-1, Chung Cheng Rd., Hsinchu City, Taipei Hsien (TW)

(**) Term: **14 Years**

(21) Appl. No.: **29/284,203**

(22) Filed: **Sep. 4, 2007**

(51) **LOC (9) Cl.** 05-06

(52) **U.S. Cl.** D5/53

(58) **Field of Classification Search** D5/1,

D5/2, 3, 5, 7, 8, 11, 13, 14, 15, 16, 19, 20, D5/23, 24, 25, 26, 27, 28, 30, 32, 35, 36, D5/37, 39, 43, 45, 47, 49, 50, 52, 53, 54, D5/55, 56, 57, 58, 59, 60, 61, 62, 63, 64, D5/65, 66, 99; D2/749, 994; D6/582, 583, D6/595, 596, 598, 603, 604, 605, 606, 608, D6/613, 616, 617, 619, 622; 428/17, 18, 428/151, 154, 156, 171, 187, 198, 199, 540, 428/542.2, 542.6, 904.4, 919; D24/124, D24/125, 126; D25/142, 152; 5/413 AM, 5/709; 162/109, 134, 140, 231; 156/148, 156/209; D7/396.4, 396.5
